Primary Examiner — Susan Bennett Hattan*Assistant Examiner* — Elizabeth S Ko(74) *Attorney, Agent, or Firm* — Michael Best &
Friedrich LLP(57) **CLAIM**

We claim the ornamental design for a circular saw, as shown
and described.

DESCRIPTION

FIG. 1 is a rear perspective view of a circular saw in
accordance with my present invention.

FIG. 2 is a left side view of the circular saw of FIG. 1.

FIG. 3 is a right side view of the circular saw of FIG. 1.

FIG. 4 is a front view of the circular saw of FIG. 1.

FIG. 5 is a rear view of the circular saw of FIG. 1.

FIG. 6 is a top view of the circular saw of FIG. 1; and,

FIG. 7 is a bottom view of the circular saw of FIG. 1.

The portions of the circular saw shown in broken lines are
included for the purpose of illustrating environment and
form no part of the claimed design. The portions of the
circular saw shown in broken lines having unequal length
segments illustrate the boundary of the claimed design and
form no part of the claimed design.
